UNITED STATES PATENT OFFICE.

FREDERICK E. STANLEY AND FRANK E. WARNER, OF WATERBURY, CONNECTICUT, ASSIGNORS TO THE SCOVILL MANUFACTURING COMPANY, OF SAME PLACE.

MACHINE FOR SETTING BUTTONS.

SPECIFICATION forming part of Letters Patent No. 639,456, dated December 19, 1899.

Application filed August 12, 1899. Serial No. 727,050. (No model.)

To all whom it may concern:

Be it known that we, FREDERICK E. STANLEY and FRANK E. WARNER, citizens of the United States, residing at Waterbury, in the 5 county of New Haven and State of Connecticut, have invented a certain new and useful Improvement in Machines for Setting Buttons, of which the following is a full, clear, and exact description.

10 This invention relates to that class of machines which are used for attaching buttons to garments by means of metallic fasteners, such as tacks, eyelets, and the like; and the object of the invention is to hold the fastening device in position when, having been taken from its feed-chute, it is carried upward and passed through the cloth or garment and into the button.

Prior to this invention the carrier for the 20 fastener has comprised a vertically-reciprocating plunger which is surrounded at its upper end by a sleeve, which sleeve is normally projected above the upper level of the plunger by means of a spring, the fastener 25 being contained within the sleeve and its head resting upon the plunger and being carried up by the plunger and forced through the garment and into the button. During this operation if the fastener, especially a tack, has for its 30 lateral support only the surrounding sleeve the point of the tack is practically unsupported laterally, and it sometimes occurs, especially in rapid running of the machine, that the said point is deflected from a vertical 35 line and fails to enter the button or is deformed. Our invention is designed to support the point or shank of the fastener as it is being carried to and forced through the garment or fabric and into the button.

40 The invention consists in a button-setting machine having a reciprocating fastener-carrier combined with sliding jaws which are adapted to engage the point or shank of the fastener as the fastener is moved up to and 45 through the garment and to support the same. These jaws also are capable of separation laterally in order to permit the intimate engagement of the mechanism by which the button and its fastener are ultimately united.

50 In the accompanying drawings, illustrating

our invention, in the several figures of which like parts are similarly designated, Figure 1 is a perspective view of the head of one form of button-setting machine especially designed for used in connection with tacks. Fig. 2 is 55 a perspective view from the rear of the sliding jaws. Fig. 3 is a front elevation of the setting mechanism, the parts being in the position when at rest and also being in the position when the plunger has been given its 60 initial movement. Fig. 4 is a front elevation of the setting mechanism, the sliding jaws having been given their first upward movement. Fig. 5 is a front elevation of the setting mechanism with the jaws separated as 65 they will be when the plunger has been given its final movement for uniting the button and fastener. Fig. 6 is a sectional side elevation taken at right angles to Figs. 3, 4, and 5 and illustrating the position of parts when at rest 70 and also when about to begin the initial movement. Fig. 7 is a similar sectional elevation showing the parts at the conclusion of the initial movement. Fig. 8 is a similar sectional elevation showing the parts as in Fig. 75 4. Fig. 9 is a similar elevation showing the parts as in Fig. 5. Fig. 10 is an elevation of a button-receiver of a modification by which our invention may be used with eyelet-fasteners, and Fig. 11 is a section showing a 80 modification of the fastener-carrier for use with such eyelet-fasteners and the button-receiver of Fig. 10.

The frame *a* may be a suitable casting adapted to be supported upon a table or stand 85 and sustaining a button-turret *b*, of any approved construction, and a button-chute *b'*, leading from said turret to the button-receiver *b*. *b*³ is a cut-off which is operated from the rock-shaft *b*⁴, which in turn is actuated by a 90 finger or switch *b*⁵, which normally closes the mouth of the button-receiver and which is vibrated by the withdrawal of the garment at each setting of the button, thus to release a button to be attached. *c* is a turret also 95 mounted upon said casting and containing the fasteners and provided with a chute *c'*, leading to the fastener-carrier, and supplied with a cut-off *c*². The fastener cut-off *c*² is normally held to close the chute by a spring 100

*c*³. *d* is a rock-lever pivoted at *d'* to the casting *a*, and to this rock-lever is pivoted an arm *d*², which actuates a pawl-and-ratchet mechanism *d*³ for rotating the button-turret *b*. 5 This lever *d* also carries an arm *d*⁴, which actuates the pawl-and-ratchet mechanism *d*⁵ of the fastener-turret, and the arm *d*⁴ has an offset *e*, which engages the finger *e'* of the cut-off *c*² to actuate it to release a fastener at the 10 proper moment.

The frame *a* is provided with a depending socket-piece *f*, to which are affixed the cloth-guides *f'*, shaped and arranged substantially as shown. Within the socket-piece *f* is arranged 15 the plunger-stem *g*, so as to have a vertically-reciprocating motion therein. This plunger-stem is connected by a link *g'* with the lever *h*, pivoted at *h'* in the bottom of the socket *f*, and arranged to be vibrated upon 20 its pivot *h'*. The plunger-stem is further provided with a lug *i*, which is connected by a link *i'* with the lever *d*, so as to vibrate said last-named lever, and thus transmit motion to the two turrets and to the cut-off *c*². The lug 25 *i* plays in the slot *i*² in the back of the socket *f*, and thus serves also to guide the movement of the plunger-stem. The plunger-stem is provided with a longitudinal cavity in its upper end, as at *j*, and within this cavity 30 is arranged a plunger *k* of considerably less diameter than the diameter of the cavity. The plunger *k* is mounted upon or may be a part of the plunger-stem *g*, and it is surrounded by a sleeve *l*, which may be slotted longitudinally and connected with the plunger by a 35 transverse pin *l'*, so as to permit the movement of the sleeve independently of the movement of the plunger. This sleeve is arranged, of course, within the cavity *j* and is normally 40 supported by means of a spring *l*², arranged in the cavity and serving to project the upper portion of the sleeve considerably above the upper face of the plunger to form a cavity to receive the fastener, as indicated in Fig. 6. 45 The level of the sleeve when at rest is below the discharge end of the tack-chute, and thus is in position to receive a tack when discharged from the chute.

On the front of the socket are arranged 50 jaws *m m*, pivoted at *m'* to each other and arrested in their descent by stops *m*² on the face of the socket. These jaws are secured to the face of the socket by means of a headed screw *n*, which is arranged in a slot formation composed of adjacent grooves *n'* in the 55 jaws, the said screw *n* being tapped in the socket, and, further, by tension-screw *o*, which is also attached to the socket and is supplied with a friction-washer *o'*, and the spring *o*², 60 interposed between said washer and the head of the screw. The jaws are further grooved out at *p* in adjacent faces and above the grooves *n' n'*, and in the slot formation consisting of the grooves *p p* is arranged a stud 65 *q*, which is tapped into the plunger-stem *g* and is reciprocated by it. The jaws *m m* are normally pressed together by springs *r* or

other suitable means. The upper ends *s* of the jaws *m m* are bent rearwardly at right angles to form a table which ultimately carries the garment into position to receive the button. These ends *s* are notched out at *s'* to form a support for the point or shank of the fastener, and they are also reamed out or hollowed out, as at *s*², to guide the fastener 75 into the notch *s'*. The jaws may be provided with knobs *t* to separate them by hand whenever desired.

The operation is as follows: Buttons having been supplied in the button-turret and 80 fasteners—for example, tacks—in the fastener-turret and a garment to be supplied with buttons being in readiness, the said garment is laid across the guides *f'*, and upward motion being imparted to the lever *h* the plunger-stem *g* is moved upwardly. Meanwhile a button having been entered into the receiver and a tack into the carrier, the upward movement of the sleeve *l* is arrested by coming into contact with the under side of 90 the parts *s s* of the vertically-sliding jaws; but the movement of the plunger continuing, the point of the tack is projected through the guide-notch *s'* and is thereby supported against lateral displacement in the further upward movement of the plunger. The pin *l'*, having reached the end of the slot in the sleeve and the spring *l*² being compressed to its limit, the plunger carries up the sleeve in its further ascent, and the sleeve carries up the 100 sliding jaws until their upward movement is arrested by contact with the receiver, as in Figs. 4 and 8, thus carrying the garment up to the said receiver and clamping it between the ends *s s* and the receiver, and the plunger continuing its further upward movement the stud *q*, acting against the upper ends of the slot formation *p p*, parts the jaws and causes them to separate from one another upon their hinge member *m'* and open laterally for the passage of the plunger and sleeve through the parted ends *s s* and against the under side of the garment to complete the union of the button and the fastener and the setting thereof upon the garment. The lever 115 *h* has now attained the limit of its upward stroke, and upon the return stroke the plunger recedes from the jaws, and passing down into its first position the carrier receives another tack from the tack-chute, the tack-chute cut-off having been previously operated to discharge a tack, and the tack being retained in said chute by the rear side of the plunger-stem during the upward movement. (See Figs. 8 and 9.) The jaws are retained 125 in their elevated position temporarily by the friction device *o* and until the stud *q* has passed from between the jaws into the slot formation and into the bottom of said slot formation, when it carries down the jaws into 130 first position, and as shown in Figs. 1, 3, and 7.

We have shown a button-receiver constructed in accordance with the patent of the Scovill Manufacturing Company, assignees

of Alfred J. Shipley, No. 579,017, dated March 16, 1897, and in which the die has a stationary portion which is surrounded by a movable sleeve and which is the button-receiver proper; but we do not limit our invention to the employment of that particular form of button-receiver. We prefer to use a button-receiver which is adapted to operate the button-chute cut-off to feed buttons to the receiver by the withdrawal of the garment from the receiver after each setting of the button, and that of the patent mentioned is of that character.

The upward movement of the jaws is limited by the friction device coming in contact with the hinge end of the jaws or by the washer of said friction device coming into contact with the head of the pivot-screw m' , and it is after this limit has been reached that the stud q in its further upward movement parts or spreads the jaws for the passage of the fastener-carrier. During both the upward and downward movement of the jaws the springs r tend to press the jaws toward each other to preserve the slot formations for coöperation with the screw n , the friction device o' , and the stud q and also serve to preserve the vertical alinement of these jaws with the socket, and while we have shown flat springs arranged at the sides of these jaws we do not limit our invention to such springs, but esteem as within our invention any other arrangement of springs which will serve to hold the jaws together and to permit their being parted, as before described.

As already indicated, the machine is applicable for use with other than tack fasteners, and in order to illustrate one such adaptation of our invention we have shown in Figs. 10 and 11, respectively, a button-receiver and an eyelet-carrier, although the receiver already described or any other receiver may be used in connection with an eyelet fastener. Referring now to these figures, u is a bracket having a shank u' , by which it may be secured in the frame, and supplied with a die u^2 and a needle u^3 for engaging the button and piercing the garment for the passage of the eyelet. u^4 is a button-holding plate having the opening u^5 to receive the shank of the button and to permit the passage of the needle and of the eyelet. This plate is suspended from the bracket u by means of posts u^6 , with springs u^7 interposed between the plate and the bracket and permitting the vertical movement of the plate with relation to the bracket. The carrier may comprise a plunger-stem v , having the plunger v' , provided with a recess v^2 for coöperation with the needle, and having a sleeve v^3 secured to the plunger, as before described, and supported around it by the spring v^4 . As the plunger rises it comes into contact with the plate u^4 and lifts it so as to cause the needle u^3 to pass through the button and penetrate the cloth and forces the eyelet through the opening in the cloth thus

made and thence into the button, where its end is upset within the button by means of the die u^2 . The springs u^7 yield to permit the rise of the plate under the action of the plunger, and when the plunger descends said plate also descends and strips the garment, with the button attached, from the mechanism and permits it to be withdrawn. The sleeve v^3 serves as a support for the garment during the operation of setting the button.

As already sufficiently indicated, we mean to include as capable of use with our present invention any form of receiver and carrier for attaching buttons by any form of fastener.

What we claim is—

1. In a button-setting machine, button-setting mechanism, having a vertically-reciprocating fastener-carrier, and a fastener-guide 85 consisting essentially of a pair of pivoted jaws normally closed, a stud affixed to said carrier and engaging the said jaws to carry them up with the carrier for a predetermined distance and thereafter adapted to open said jaws to 90 permit the passage of the carrier between them, substantially as described.

2. In a button-setting machine, the combination of a button-receiver, a vertically-reciprocating fastener-carrier, and a fastener-guide comprising jaws pivoted together at their lower ends, having horizontal upper ends notched to receive the point or shank of the fastener, and springs for normally holding the jaws closed, and a stud carried by the fastener-carrier and engaging the jaws to lift them with the carrier and to part them for the passage of the carrier, substantially as described. 95

3. In a button-setting machine, a button-receiver, a vertically-reciprocating fastener-carrier, and a socket in which said carrier is arranged, combined with a pair of spring-actuated jaws, pivoted together, mounted upon the socket and frictionally supported thereon, 105 and a stud projecting from said carrier and engaging the said jaws to elevate them with the carrier and to part them for the passage of the carrier, substantially as described. 110

4. In a button-setting machine, button-setting mechanism, including a reciprocating fastener-carrier, a button-receiver, and a pair of spring-actuated jaws movable longitudinally with the carrier, having horizontally-arranged ends forming a guide for the fastener and a 120 support for the garment, a headed screw holding the said jaws in place and permitting longitudinal movement thereof, a connection between said jaws and the fastener-carrier, and a tension device for holding the said jaws in 125 elevated position when so moved by the fastener-carrier, substantially as described. 115

5. In a button-setting machine, a button-receiver, a vertically-reciprocating fastener-carrier, a socket in which said carrier is arranged, a pair of jaws pivoted together and mounted upon the socket, a connection between the jaws and the carrier by which the said jaws are moved with said carrier, said 130

connection having a certain amount of lost motion relatively to the jaws on the return stroke, and a friction device for temporarily retaining the jaws in elevated position upon 5 the return stroke of the carrier, substantially as described.

6. In a button-setting machine, a button-receiver, a vertically-reciprocating fastener-carrier, a socket in which said carrier is arranged, a pair of spring-closed jaws pivoted together at one end and having two distinct slot formations between their adjacent edges, a headed fastening arranged in one of said slot formations and securing said jaws slidably upon the socket, a friction device arranged in the same slot formation, and a headed stud arranged in the other slot formation and fast to the carrier and adapted to move the jaws longitudinally with the carrier 15 20 and thereafter part the jaws from one another for the further movement of the carrier, substantially as described.

7. In a button-setting machine, the combination of a vertically-reciprocating fastener-carrier, a frame in which it travels, a guide 25 for the fastener mounted to slide up and down

upon said frame, means to connect the guide with the carrier and to cause said guide to be moved up and down with the carrier, means to fasten the guide to the frame and limit its 30 upward movement, and stops to arrest its downward movement, substantially as described.

8. In a button-setting machine, button-setting mechanism including a fastener-carrier, 35 and a button-receiver, said receiver comprising a bracket having a die and needle, a plate recessed to receive and support the button, posts attached to said plate and having a sliding union with the bracket, and springs interposed between the plate and bracket and 40 permitting the plate to yield as the fastener-carrier moves upwardly against and with it, to assemble the button and eyelet and unite them, substantially as described. 45

In testimony whereof we have hereunto set our hands this 11th day of August, A. D. 1899.

FREDERICK E. STANLEY.
FRANK E. WARNER.
